His ATTORNEY.

UNITED STATES PATENT OFFICE

CLARK A. THARP, OF LEAVENWORTH, KANSAS

COPY HOLDING STAND

Application filed December 19, 1928. Serial No. 327,087.

My invention relates to improvements in copy holding stands, particularly well adapted for use in supporting a note book adjacent to a type writing machine.

One of the objects of my invention is to provide a novel stand of the kind described, which is simple, cheap, strong, durable, not likely to get out of order, which permits of adjustments to a large number of positions, which is easy to adjust, and quickly and securely adjusted so as to support a note book in most any desired position, and which is stable and not liable to tip over.

The novel features of my invention are hereinafter fully described and claimed.

In the accompanying drawings, which illustrates the preferred embodiment of my invention,

Fig. 1 is a front elevation of my improved copy holding stand.

Fig. 2 is a side elevation of the same as shown in Fig. 1.

Fig. 3 is a plan view of the standard and a part of the angular member and parts connected therewith.

Fig. 4 is a side elevation of the stand, partly broken away, and shown in a position different from that shown in Figs. 1 and 2.

Fig. 5 is a section on the line 5—5 of Fig. 4, enlarged.

Fig. 6 is an enlarged section on the line 6—6 of Fig. 4.

Fig. 7 is a plan view of the line indicating member.

Similar reference characters designate similar parts in the different views.

My improved copy holding stand is provided with a standard comprising a base 1 having a central vertical hole in which is revolvably mounted on a vertical axis a post 2 having a lateral horizontal arm 3, which is embraced revolvably by and between the arms of a U shaped clamping member 4. Extending, at right angles to the arm 3, through the arms of the member 4 is a pivot bolt 5 which also extends through the arms of another U shaped member 6. A nut 7 on the bolt 5 upon being adjusted, presses the arms of the members 4 and 6 against each other, thereby causing the member 4 to tightly grip the lateral

arm 3 of the post 2, and also causing the arms of the U shaped member 6 to tightly clamp one arm 8 of an angular intermediate member 9. When the nut 7 is loosened, the arm 8 is longitudinally slidably and circumferentially 55 adjustable in the member 6, and the member 4 can be slid lengthwise and turned on the lateral arm 3 on an axis at right angles to the axis, comprising the pivot bolt 5, on which the members 4 and 6 are revoluble. By 60 tightening the nut 7, the parts just described are held in their adjusted positions.

The other arm 10 of the angular member 9 supports a copy holding member 11, so as to permit movement of the copy holding member 11 on the arm 10, as will now be described.

The under side and lower end portion of the copy holding member 11 is provided with a cylindrical stem 12 which is embraced by and longitudinally slidable and circumferentially adjustable in a U shaped member 13, through the arms of which extends a pivot bolt 14 provided with a nut 15, said bolt 14 also extending through the arms of another U shaped member 16, which embraces, and is 75 slidable and circumferentially adjustable on the arm 10 of the angular member 9.

By tightening the nut 15, the members 13 and 16 are caused to tightly respectively 80 clamp the stem 12 and arm 10, in the same manner as the members 4 and 6 are made to clamp the lateral arm 3 and the arm 8, as was described.

The lower end of the copy holding member 11 is provided with shelf 17, usual with such devices, which shelf is provided with a hole through which extends the lower end of a supporting guide member, preferably a wire 18, the upper end of which is provided with 90 a rearwardly extending arm which extends through a hole provided through the member 11 adjacent to the upper end and left edge thereof.

An indicating member comprising, preferably a wire having a straight portion 19, the lower end portion of the wire, which is a spring wire, being formed into an arcuate coil 20, which extends laterally from the portion 19 at right angles thereto.

The member 11 is flexible and resilient, so that it may be flexed to permit of the insertion into or removal from the hole in the shelf 17 of the free end of the wire guide 18.

- 5 The internal diameter and acute bend of the coil 20 are such, that, when the coil is slid onto the wire 18, the latter will cause the coil 20 to straighten, thus causing the coil to bind on the wire 18, so as to releasably hold 10 it in the position to which it may be adjusted upwardly or downwardly on the guide wire 18.

In the operation of the stand, the nuts 7 and 15 are loosened, following which, the 15 angular member 9 may be adjusted on the standard to any desired position within the range of its adjustability, after which the nut 7 is tightened. The copy holding member 11 is then adjusted on the arm 10 to the desired position, following which the nut 15 is tightened. The parts are thus firmly fastened in their adjusted positions with the tightening of the two nuts 7 and 15. The connections between the member 11 and the arm 20 25 10 and between the arm 8 and the arm 3, permit of a large number of positions of adjustment for the device.

By having the arm 8 of the angular member 9 slidably adjustable longitudinally in 30 the U shaped member 6, by loosening the thumb nut 7, the copy may be moved upwardly or downwardly without changing its angular position, and so not requiring any readjustment of the support 11, after such upward 35 or downward adjustment, when the arm 8 is vertical or inclined in a vertical plane, as shown in Fig. 2. Or the copy may be moved forwardly or backwardly, without moving the stand 1 and without changing the angular 40 position of the copy holder 11, Fig. 4.

By providing the two U shaped members 4 and 6, respectively engaging the arm 3 of the standard and the arm 8 and arranged to be clamped thereto by the single screw 5 and 45 thumb nut 7, the arm 8 may be adjusted in the member 6 and the member 4 adjusted on the arm 3, by merely loosening and then tightening the thumb nut 7 respectively before and after the adjustment, the single clamping 50 means effecting the double function.

I do not limit my invention to the structure shown and described, as modifications, within the scope of the appended claims, may be made without departing from the spirit of 55 my invention.

What I claim is:—

1. In a copy holding stand, a standard, a copy holding member, an intermediate member, means supporting said copy holding member on said intermediate member, and a joint connection between said intermediate member and said standard comprising two members pivoted to each other, one adjustably slidably engaging and supporting said intermediate member, and the other being 60 65 70 75 80 85 90 95 100 105 110 115 120 125 130

pivoted to said standard on an axis at right angles to the axis of said two members, whereby the intermediate member may be raised or lowered without changing the angular position of said copy holding member, and by which said intermediate member may be swung forwardly and backwardly and laterally.

2. In a copy holding stand, a standard, a copy holding member, an intermediate member, two members pivoted to each other, one slidably and pivotally engaging and supporting said intermediate member, the other pivoted to and supported by said standard, and means supporting said copy holding member on said intermediate member.

3. In a copy holding stand, a standard, a copy holding member, an intermediate member, means for supporting said copy holding member on said intermediate member, said standard comprising a base and a post revolute thereon on a vertical axis and having a horizontal arm, and two members pivoted to each other, one pivoted to and supported by said arm, the other slidably and pivotally engaging and supporting said intermediate member.

In testimony whereof I have signed my name to this specification.

CLARK A. THARP. 95
